UNITED STATES PATENT OFFICE.

ANNA LOUISA RHEDANS AND ANDULO MARIE HITZERT, OF ST. LOUIS, MISSOURI.

GRAVE LINING.

1,426,600.

Specification of Letters Patent. Patented Aug. 22, 1922.

Application filed February 9, 1922. Serial No. 535,188.

To all whom it may concern:

Be it known that we, ANNA LOUISA RHEDANS and ANDULO MARIE HITZERT, citizens of the United States, and residents of 5 St. Louis, Missouri, have invented certain new and useful Improvements in Grave Linings, of which the following is a specification containing a full, clear, and exact description, reference being had to the accompanying drawings, forming a part hereof.

Our invention consists in the novel construction and combination of parts herein-after particularly described and distinctly 15 claimed.

The object of our invention is to provide an improved ornamental, or finishing, lining for graves; which shall be of a light, simple, and non-expensive construction, adapted to 20 be quickly unfolded and placed in position in a grave, in order to ornament the walls of the same, and present them in a more pleasing form to the eyes of the mourners and spectators, at burial services.

25 In the drawings,

Fig. 1 is a top plan-view of an ordinary grave, having our invention applied thereto.

Fig. 2 is a vertical longitudinal section of the same, taken on the line 2—2 of Fig. 1.

30 Fig. 3 is a detail inverted sectional plan-view of one corner of our grave lining, opened out as when being used, the section being taken on the line 3—3 of Fig. 2.

Fig. 4 is a detail view of the head-end 35 of one of a number of vertical holding and stretching-rods, made use of in applying the invention to a grave.

Fig. 5 is a view similar to Fig. 2, but illustrating a modification of our invention.

40 Fig. 6 is a detail top-plan view of one corner of the modification.

Fig. 7 is a horizontal section, taken on the line 7—7 of Fig. 5, and showing one corner of the modification, and

45 Fig. 8 is a side-elevation of a blank for the side or end of the modified vertical lining-wall and finishing-flap.

The numeral 1 designates a side-section of lining-material, which may be made of any 50 appropriate material, such as paper or cloth, of any color, and it should be of sufficient size to completely cover and line one of the vertical sides of the grave 7, when placed and supported therein by the means herein- 55 after described.

There are, of course, two of said side-sections 1, and there are two end-sections 2; the side-sections being placed in the grave opposite each other, and the two end sections being located in the grave opposite each other, at opposite ends of the grave.

Preferably, the side and end sections are formed integral, by folding a long strip or bolt of material, to form a rectangular body having a size to fit snugly within the grave 65 and cover and ornament the vertical walls of the latter.

At the upper edge of the lining is a finishing-flap 3, which is formed by turning or folding outwardly a marginal portion at 70 the top of the side and end sections, and gathering or ruffling the material at the union of the corner-portions, (or otherwise arranging suitable material) to provide an ornamental rosette or construction 9 at the 75 corners of said finishing-flap portions.

The said rectangular grave-lining body is also preferably made with vertical corner-hems or rod-pockets 4, by sewing or otherwise fastening the material together, as 80 shown (for instance) in Fig. 3.

Said rod-pockets 4 are provided to receive vertical holding and stretching rods 5, the lower ends of which are pointed, so that they may readily enter or be driven in the 85 earth at the bottom of said grave 7, as near as possible to the corners thereof.

The upper portions of said rods 5 are provided with a laterally-projecting holding-arm 6, from the outer ends of which sharpened spikes or prongs 6^a extend downwardly, to enter the earth at the top of the grave, and some distance therefrom, and rest upon the underlaid finishing-flaps 3, wherever required, and especially at the corners, to 95 securely hold down the said ornamental corner-pieces 9.

The modified construction.

In Figs. 5 to 8, inclusive, I have shown 100 a modified construction of the grave lining, in which the side and end sections, and the finishing-flaps, are made of thick paper or card-board separately formed as blanks, as shown in Fig. 8.

105

The blank shown in Fig. 8 may be long enough for the side-sections 1, or it can be cut shorter, to provide the end-sections 2, the construction of both side and end sections being the same, except as to length. 110

Said sections are preferably provided with scored or indented parallel longitudinal lines 14 and 15, the first of which is provided to guide the user in folding outwardly the integral finishing-flap 3, as well as enabling the said flap to be folded flat against the body of the section, in packing and shipping. The second line 15 is provided as merely a folding line, to enable the section to be folded into smaller space, in packing and shipping, and in handling, before the sections are located in the grave.

The adjacent vertical edges of the side and end sections are located and held in vertical grooves, formed by parallel vertical flanges 12 on tubular pockets 4^a, in which the previously-described holding and stretching rods 5 are located. Fig. 7.

At opposite ends of the said side and end sections 1 and 2 are integral corner-flaps 10, which can be folded inwardly on the dotted or scored line 16, until the device is to be used, when said flaps are extended to the position in which they are shown in solid lines; said flaps being mitered, or cut off at an angle, to fit like angular portions of the adjacent section, when the sections are placed within the grave.

A semicircular recess 11 is formed in the inner edge of the base of each corner-flap 10, to receive the said holding and stretching rods 5.

The operation.

In using our invention, the various parts are placed and secured in the grave as shown in Figs. 1 and 2, if the construction of Figs. 1 to 4 is made use of.

If the modified construction is used, the parts are to be arranged as shown in Figs. 5 to 8, inclusive, and in either event no further description will be necessary, except to point out the fact that the interior,

as well as the margin of the grave will be pleasingly lined and ornamented by our invention. 45

In all cases, the lower edge of our grave lining should extend a distance below the top of the usual rough-box 8, in which the coffin or casket is placed. 50

We claim:

1. A grave lining, comprising a rectangular hollow body, and finishing-flaps at the upper sides and ends of said body adapted to be folded outwardly and cover the earth adjacent the mouth of the grave; in combination with vertical rod-pockets at the corners of said hollow body, and holding and stretching rods adapted to be placed in said pockets and have their lower ends driven into the earth at the bottom of the grave. 55

2. The combination of the elements recited in the above claim 1, and lateral arms on the upper ends of said rods, for extending over, and holding down, the said finishing-flaps. 65

3. The combination of the elements recited in the above claim 2, and downwardly projecting earth-spikes at the outer ends of 70 said lateral arms.

4. The combination of the elements recited in the above claim 2, and ornamental bodies at the corners of the finishing-flaps, adapted to be held down by the said lateral 75 arms of said holding and stretching rods, when said arms are extended over said ornamental bodies.

In testimony whereof, we have signed our names to this specification in presence of 80 two subscribing witnesses.

ANNA LOUISA RHEDANS.

ANDULO MARIE HITZERT.
